UNITED STATES PATENT OFFICE.

RALPH S. BALDWIN AND WILLIAM A. JOHNSTON, OF SPOKANE, WASHINGTON.

MINERAL SEPARATOR.

Application filed August 3, 1925. Serial No. 47,682.

Our present invention relates to improvements in mineral separators and particularly a laundering table forming part of the separating machine used for extracting precious metals, as gold, in placer mining. The laundering table is designed to receive the gangue from any suitable source, which is here indicated as a precipitating tank, in which the gangue is treated before reaching the laundering or washing table, and means are provided for precipitating and collecting the grains of gold washed from the table, and for disposing of the tailings from the table, which tailings may be further treated in the separating machine by other units.

By the utilization of our invention the gangue is effectively washed to loosen and remove the dirt coatings or coverings from the grains of gold in order that the latter may be separated therefrom as by precipitation, and subsequently be collected for further use of treatment.

The invention involves the use of an oscillatable or rocking table of specific construction in which are incorporated certain novel combinations and arrangements of parts for effectively washing and disposing of the material as will hereinafter be more fully set forth and claimed.

In the accompanying drawings we have illustrated one complete example of the physical embodiment of our invention wherein the parts are combined and arranged according to the best mode we have so far devised for the practical application of the principles of our invention. While we will hereinafter refer to the extraction of gold, it will be understood that the machine is applicable for use in the extraction and recovery of other precious metals.

Figure 1 is a view in side elevation of a mineral separating machine in which the washing or laundering table of our invention is utilized as a unit.

Figure 2 is an enlarged top plan view of the laundering table.

Figure 3 is an enlarged transverse vertical sectional view of the laundering table and its support, indicating by dotted lines the limit of movement of the oscillatable table.

Figure 4 is a detail view of the adjustable

crank operating means for oscillating the table.

In order that the general relation and assembly of parts may readily be understood we have shown in Figure 1 the entire separating machine of which the oscillatable laundering table forms a unit, but it will be understood that the table and its connections may readily be adapted for other uses than that illustrated in the assembly view.

In the preferred form of the invention the frame 1 is made up of pairs of inwardly inclining metal bars having a base 2, and at the tops of the bars a longitudinally extending wooden beam 3 is supported and rigidly secured by bolts to the frame. At its ends this supporting beam is provided with bolts or threaded posts 4 and 5 which pass through bolt holes in the beams and by means of lock nuts 6 and 7 these supporting posts or uprights may be rigidly retained in adjusted position. Above the supporting beam and parallel therewith is located a rocking beam 8 disposed longitudinally of the machine and adapted to rock or oscillate on its longitudinal axis. At its ends this rocking beam is fashioned with trunnions 9 that are journaled in bearings 10 at the top or upper ends of the posts 4 and 5, and the laundering table is rigidly supported on this rocking beam to oscillate therewith.

The table top is made up of a plate or sheets of galvanized iron and as indicated the top 11 is of concavo convex form in cross-section with its lateral edges higher than the longitudinal center. On the top 12 surface of the table top we use a mat 12 which preferably is fashioned with a top corrugated surface with the alternating ribs and grooves running longitudinally of the table to assist in washing or laundering the gangue for the purpose of loosening and removing the dirt covering or coating from granular gold, as the table is rocked. As seen in Figure 1 the table declines slightly to the right and is adjusted by positioning the two posts or bolts 4 and 5 in desired relation in order that the material discharged onto the table will gradually work toward the right end in Figure 1.

As the table is oscillated the lighter materials are gradually worked laterally of the table top and separated from the heavier materials, and the lighter materials eventually pass into side chutes 13 and 14 located at opposite sides of the table. To prevent escape by splashing of the materials we provide inwardly curved flanges 15 and 16 which project upwardly from the outer walls of the chutes and deflect the materials downwardly to the chutes.

As best seen in Figure 1 these vertically disposed side chutes are provided with inclined bottoms as 17 which converge at approximately the longitudinal center of the table and the chutes terminate respectively in sluice ways 18 and 19. As seen in Figure 3 these sluices or sluiceways are inclined and extend toward the center of the table below the supporting beam, and they are joined at 20 and provided with a single or common outlet 21.

Above the oscillating table we dispose a spray pipe 22 which is connected with a main water supply pipe 23, and the water is sprayed uniformly upon the material on the table top to assist in washing or laundering the material. It will be apparent that as the table is rocked or oscillated as indicated by the dotted lines in Figure 3, the material will be washed as it is passed back and forth transversely of the table top and the lighter materials will find their way to the vertically disposed chutes. Due to this washing and agitation the separated lighter materials fall by gravity through the chutes and run or flow through the two sluices and then pass out or are discharged through the outlet 21 to a precipitating tank 24 located below the table in position to receive the materials from the sluices.

The precipitating tank is fashioned with converging bottom walls 25 which terminate in a collecting cup 26, and the removable cover 27 of this cup may be withdrawn to extract from the tank the grains of gold therein. By precipitation the heavier materials are deposited on or flow down the converging walls to the collecting cup, while the lighter materials with the water content flow out of the tank through a laterally extending trough 28, and the tailings passing through this trough may be further treated if desired. The inlet to the trough is located a sufficient distance above the bottom of the tank, or the collecting cup, as not to interfere with the precipitation of the heavier materials, but to carry off the lighter more buoyant materials.

For oscillating the table, power is transmitted from a transversely arranged operating shaft 29 journaled to revolve in bearings in supporting frames 30. A crank disk 31 is keyed on the shaft and provided with a series of pin-holes 32 spaced at various dis-

tances about the center of the disk or the axis of the shaft, and a pitman 33 is connected by its pivot pin 34 to a selected one of these various operating points of the disk for the purpose of determining the length of the throw or stroke of the pitman, thus varying the oscillating movement of the table. At its upper end the pitman is connected by a universal or ball and socket joint 35 to a rigid portion 36 of the table, and it will be apparent that the rotary movement of the shaft is translated into oscillating movement of the table by these power transmitting devices.

The operating shaft is driven from an engine shaft 37 (Fig. 2) by means of a pulley 38 on the engine shaft shown in dotted lines, the belt 39 and the pulley 40 on the shaft 29.

In the installation of the apparatus illustrated in Figure 1 the gangue is elevated by a pump 41 to the hopper 42, where it is screened. The coarser material flows into a tailings trough 43 and the extracted material falls by gravity into a precipitating tank 44, where grains of gold are precipitated into the collecting cup 45 and the residue of the material is conveyed through the housing 46 and deposited upon the laundering table heretofore described. The several parts of this mechanism are operated by power transmission devices from the engine shaft 37, a description of which is not necessary to an understanding of the present invention. As the gangue issues from the endless conveyor in the housing it is sprayed with water from a nozzle or nozzles as 47 and the supply of water for this spray is regulated from the main water pipe 23 by the valve 48.

The materials flowing down the inclined table top pass therefrom over the outlet end 49 to a sluice way 50 and thence to a precipitating tank 51 which is provided with a collecting cup 52 similar to the cups 27 and 45 heretofore described. The tailings from the precipitating tank 51 may be conducted to a pair of copper plates 52 and 53 where the fine grains of gold are amalgamated with mercury in usual manner, and the final tailings are disposed of through a trough 54.

From the above description taken in connection with our drawings it will be apparent that the laundering table may be used as a separate unit in the extraction of gold and other precious metals, or it may be used as an intermediate unit together with additional units in the mineral separating machine shown.

Having thus fully described our invention what we claim as new and desire to secure by Letters Patent is—

1. The combination with a supporting frame of a pivoted table having a concave surface and adapted to oscillate on its longitudinal center, and a mat on the table having a longitudinally extending corrugated

surface, said table having an outlet at one end and lateral launder chutes, and discharge troughs opening from said chutes.

2. The combination with a supporting frame, of a pivoted table and means for oscillating said table on its longitudinal axis, said table having an outlet at one end and lateral launder chutes, side baffle plates lo-

cated at the respective outer sides of said chutes and projecting above the plane of the 10 table top, and downwardly extending discharge troughs opening from said chutes.

In testimony whereof we affix our signatures.

RALPH S. BALDWIN.

WILLIAM A. JOHNSTON.
